CLAIM

The ornamental design for a display screen with graphical user interface, as shown and described.

DESCRIPTION

FIG. 1 is a front elevation view of a display screen with graphical user interface in accordance with the new design; and,

FIG. 2 is a front elevation thereof, shown in an alternate environment.

The broken lines showing the display screen define the bounds of the claimed design and form no part thereof. The broken lines showing the remainder of the graphical user interface form no part of the claimed design.

1 Claim, 2 Drawing Sheets

FIG. 1

FIG. 2
